The accompanying photograph illustrates a face view of a carpet having my new design.

A is a flower-group, whose center consists of open rose-like figures surrounded by leaves and foliage, and from this center extends the branch b, on which grow serrated leaves and flowers, and, also, in the opposite direction extends the branch a, on which grow rose-like flowers, beyond which extends a leafy spray, and from below the central roses of the group A extends a vine-like leafy branch.

B is a group composed of leaves and flowers, having extending below it the vine-like figure e, bearing leaves and rose-like flowers, and having long slender stems projecting from it, while on the other side of the group B extends the branch d, bearing flowers resembling half-open rose-buds surrounded by leaves. The leafy spray f branches off from the group B near the branch d. On another side of the group B extends the leafy branch h.

The figure D consists of a rose-like central figure surrounded by leaves and having fern-like branches projecting on one side thereof. The figure C consists of a central flower, having projecting from it leaves and leafy sprays. The figure g is composed of two slender stems bearing leaves and flowers and crossing one another.
